US0D1069767S

(12) **United States Design Patent** (10) **Patent No.:** **US D1,069,767 S**
(45) **Date of Patent:** **** Apr. 8, 2025**

(54) **ACCESSORY FOR MICROPHONES**

(71) Applicant: **VITEC IMAGING SOLUTIONS S.p.A.**, Cassola (IT)

(72) Inventors: **Timo Klinge**, Hamburg (DE); **Federic Sonnenberg**, Berlin (DE)

(73) Assignee: **VITEC IMAGING SOLUTIONS S.p.A.**, Cassola (IT)

(**) Term: **15 Years**

(21) Appl. No.: **29/848,056**

(22) Filed: **Jul. 29, 2022**

Related U.S. Application Data

(62) Division of application No. 29/757,710, filed on Nov. 9, 2020, now Pat. No. Des. 991,228.

(30) **Foreign Application Priority Data**

May 11, 2020 (EM) 007878368

(51) **LOC (15) Cl.** **14-01**

(52) **U.S. Cl.**

USPC **D14/225**

CLAIM

The ornamental design for an accessory for microphones as shown and described.

DESCRIPTION

FIG. 1 is a perspective view of the accessory for microphones of our design;

FIG. 2 is a right-side view thereof;

FIG. 3 is a left-side view thereof;

FIG. 4 is a top view thereof;

FIG. 5 is a bottom view thereof;

FIG. 6 is a front view thereof; and,

FIG. 7 is a rear view thereof.

The broken line showing is included for the purpose of illustrating environment and forms no part of the claimed design.

1 Claim, 7 Drawing Sheets
